UNITED STATES PATENT OFFICE

100,574

DESIGN FOR A COMBINED BOTTLE AND HOLDER THEREFOR

Frank McIntosh, New York, N. Y., assignor to Lenthalic Incorporated, New York, N. Y., a corporation of New York

Application May 11, 1935, Serial No. 56,785

Term of patent 14 years

To all whom it may concern:

Be it known that I, Frank McIntosh, a citizen of the United States, residing at New York city, in the county of New York and State of New York, have invented a new, original, and ornamental Design for a Combined Bottle and Holder Therefor, of which the following is a specification, reference being had to the accompanying drawing, forming part thereof.

In the drawing:

Figure 1 is a top plan view of a combined bottle and holder therefor, showing my new design;
Figure 2 is a front view; and

I claim:

The ornamental design for a combined bottle and holder therefor, substantially as shown.

In witness whereof I affix my signature.

FRANK MCINTOSH.
